UNITED STATES PATENT OFFICE.

ROBERT E. SHEAL, OF CLEVELAND, OHIO.

ANCHORING DEVICE.

Application filed September 10, 1924. Serial No. 736,820.

This invention relates to hoisting and conveying machinery of the traveling bridge type and has to do with means for anchoring the traveling structure when in a stationary position, such for example as that illustrated in the Letters Patent of P. J. Fickinger, No. 1,319,996, dated October 28, 1919, although it will be understood that my improvements may be applied to any structure of this nature designed to move along a fixed path such as ore bridges, unloading machinery, and the like.

A traveling structure of this nature may be of great size and considerable weight and consequently have such momentum that if it once becomes started by wind pressure on its super structure or from any other cause it is likely to disregard all anchoring provisions even when moving at low speed.

20 My invention is not designed to stop the movement of the structure when in motion but has for its object the provision of new, improved, and simplified mechanism for securing it rigidly against becoming accidentally set in motion; the provision of new and simplified means for operating and manipulating the securing devices; the provision of a device of this nature which can be made and assembled in the shop and 25 afterward sold and applied as a unit to existing bridges; the provision of a structure whereby the necessary anchoring strength can be obtained with less strain than heretofore; while further objects and 30 advantages of the invention will become apparent as the description proceeds. More specifically this invention consists of an improvement upon the device contained in my Patent No. 1,450,735, issued April 3, 1923, in respect of lightness, convenience of manipulation, and ease of installation.

In the drawings accompanying and forming a part of this application Fig. 1 is a side elevation of my improved anchoring device showing the mode of its application to a bridge; Fig. 2 is an end elevation of the device shown in Fig. 1; Fig. 3 is a horizontal sectional view corresponding to the line 3-3 of Figs. 1 and 2 and looking downwardly; Fig. 4 is a top plan view of my improved anchoring mechanism, the operating wheels being shown in section; and Fig. 5 is a detail sectional view through one of the trunnions whereby the adjusting screws are supported.

A bridge of the type here intended com-

prises a pair of upright legs or towers connected by a suitable truss work. Each of these legs or towers is provided with a suitable number of supporting wheels engaging a runway along which the device is movable. I have shown herein a pair of spaced horizontal sill girders 1-1 constituting the end of one of the legs or towers and provided with carrying wheels 2-2 running on tracks 3-3. Any suitable or desirable means may be employed for propelling this bridge, preferably comprising a rack 4 lengthwise of the runway and cooperating with suitable driving means as set forth in the Fickinger patent above mentioned, since such rack lends itself with particular convenience to the operation of my locking device, although so far as this device is concerned it is immaterial whether the same engages the rack or some other form of abutment carried by the runway, and whether if such rack be employed, it have any other function than this securing one.

To the girders 1-1 near their ends I attach two cross pieces 5-5, and between these cross pieces I secure two spaced parallel sills 6-6 constituting a narrow frame located inside the limits of the girders 1-1. Carried by these sills is an upwardly projecting frame work of some type, here comprising uprights 7 and braces 8. To the upper end of this frame work is affixed a base plate 10 on which the controlling mechanism is mounted.

Traversing the sills 6-6 is a pivot pin 12 on which are mounted two links 13 which project beyond the region of the wheels 2 where they are pivoted to the ends of another cross pin 14. This last pin is journaled in the side plates 15-15 of a massive locking spud or anchor, the lower ends of these plates being securely fastened to a toothed engaging member 16, here illustrated as formed for engagement with the rack 4, although its shape depends upon the character of the device with which it is to cooperate. At their upper ends these plates are traversed by another cross pin 17.

Projecting from the forward face of the base plate 10 are two pairs of spaced brackets 20-20, one pair above the other, and journaled between the brackets of each pair is a horizontal trunnion 21 formed with a diametral hole 22 in which is journaled the shank 23 of a massive screw 24. The uppermost screw projects approximately horizon-

tally and engages the cross pin 17 through which it passes being suitably threaded thereto, while the lowermost screw projects downwardly at a sharp angle where it is 5 threaded into the cross pin 14. The uppermost screw is provided adjacent the trunnion 21 with a miter gear 25 meshing with a companion gear 26 carried by the horizontal shaft 27 whose inner end is journaled in a socket 28 formed in the end of the trunnion and whose outer end is journaled in a bracket 29 carried by the base plate 10. Rigidly secured to the outer end of the shaft 27 is a hand wheel 30 by which it can be 10 operated; while rotatively sleeved upon the shaft 27 between the wheel 30 and the bracket 29 is a second larger hand wheel 31 to whose hub is fastened a pinion 32 meshing with a spur gear 33 carried by a horizontal shaft 34 whose inner end is provided with a miter gear 35 meshing with a miter gear 36 carried by the lower screw. The upper edges 15 of the sills 6 serve as supports for a horizontal metal plate 40 which overhangs the anchor at each side constituting a platform 20 for the operator, its edge being here shown as stiffened by an angle iron 41.

Manipulation of the wheel 31 raises or 25 lowers the pin 14 through the agency of the corresponding screw, and with it moves the anchor. The pitch of this screw is so chosen that the weight of the anchor will be safely supported thereby, although it is desirable that its pitch, coupled with the weight of 30 the rim of the wheel 31, should cause the wheel to revolve for a substantial interval in lowering the anchor into place when once set spinning by the operator during the operation of setting the anchor. Manipulation 35 of the wheel 30 rocks the upper end of the plate 15 depending upon the direction of turning, and thereby brings the toothed portion into proper engaging relation relative to the part it contacts.

40 It will be understood that many changes in detail can be made within the scope of my invention and that I do not limit myself in any wise except as specifically recited in my several claims.

45 Having thus described my invention what I claim is:

1. As an article of manufacture and sale 50 an anchoring device for the purpose described comprising a frame adapted to be attached to the girders of a movable bridge, a pair of links pivoted to said frame, an upright anchor pivoted to said links, an irreversible screw operatively connected to said anchor in direct lifting relation, a hand 55 wheel, and gearing operatively connecting said wheel and screw.

60 2. An anchoring device for the purpose described comprising a frame, a framework located above the same, an upright elongated 65 anchor member, a pair of cross pins carried

by said anchor member near its upper and lower end respectively, a pair of links pivoted to the lower cross pin and to said frame, a pair of screws operatively secured to said frame work and engaging said cross pins 70 respectively, and means for rotating said screws independently of each other.

3. In mechanism of the character described, the combination with a frame and a runway along which the same is movable, 75 of an elongated anchoring member, link devices pivoted to said anchoring member near one end and to said frame at a point near said runway, a pair of elongated screws pivoted to said frame upon horizontal axes at 80 a greater distance from said runway, the pivot axes being perpendicular to the axes of the screws, screw threaded members carried by said anchoring member adjacent to its upper and lower ends respectively with 85 which members said screws engage, a pair of hand wheels, and gearing between said hand wheels and screws respectively.

4. In mechanism of the character described, the combination with a frame and a runway along which the same is movable, 90 of an elongated anchoring member, a cross pin journaled in said anchoring member near one end and having screw thread provisions, 95 links pivoted to said pin and to said frame at a point near said runway, a second screw threaded member carried by the opposite end of said anchoring member, a bearing carried by said frame at a distance above 100 said runway approximately equal to the length of said anchoring member, a pair of horizontal trunnions journaled therein, long screws journaled in each trunnion perpendicular to its axis, one of said screws engaging 105 said cross pin and the other engaging said second threaded member, rotatable shafts coaxial with said trunnions, gearing between said shafts and screws, and means for rotating said shafts independently.

5. In mechanism of the character described, the combination with a frame and a runway along which the same is movable, 110 of an elongated anchoring member mounted in an approximately upright position, link means connecting the lower end of said member with a lower part of the frame, a pair of horizontal trunnions pivoted to said frame approximately level with the top of 115 said member, a long screw journaled in each trunnion perpendicular to its axis and operatively connected to opposite ends of said member, a horizontal shaft coaxial with each trunnion, gearing between each shaft and the corresponding screw, a pair of concentric hand wheels movable independently of each other, and operative connections between each wheel and one of said shafts.

120 In testimony whereof, I hereunto affix my signature.

ROBERT E. SHEAL.
